(57) **CLAIM**

The ornamental design for a hockey glove, as shown and described.

DESCRIPTION

FIG. 1 is a top plan view of a hockey glove showing our new design;

FIG. 2 is a left elevational view thereof;

FIG. 3 is a right elevational view thereof;

FIG. 4 is a bottom plan view thereof;

FIG. 5 is a rear elevational view thereof, the area shown encircled by broken lines forms no part of the claimed design; and,

FIG. 6 is a front elevational view thereof.
